GAME

Frank C. Wachs, Milwaukee, Wis.

Application May 20, 1932, Serial No. 612,458
Renewed August 23, 1934

15 Claims. (Cl. 273—138)

This invention relates to games and refers more particularly to a game wherein the arresting of a rotatably mounted member cooperates with a scoring member movably carried thereby to indicate the score obtained.

It is an object of this invention to provide a game, which, through the uncertainty of the result, will arouse the interest of both children and adults and provide fascinating entertainment.

It is a further object of the invention to provide a game of the character described which is particularly adapted for use in the home.

A further object of this invention resides in the provision of a device of the character described so constructed that several games may be played with the device.

It is a further object of this invention to provide a game in which the rotatably mounted member may be operated by the individual and in which the scoring member during its period of movement is exposed to the view of the players, the interest in the game being thus maintained at a high point.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated two complete examples of the physical embodiment of my invention constructed according to the best modes I have so far devised for the practical application of the principles thereof, and in which:

Figure 1 is a cross section through a game embodying this invention and illustrating the same set up for use;

Figure 2 is a plan view with parts broken away, taken on the plane of the line 2—2 of Fig. 1;

Figure 3 is a detail sectional view of the game taken on the plane of the line 3—3 of Fig. 2;

Figure 4 is a fragmentary plan view of a modification of the game with parts broken away and in section; and

Figure 5 is a cross sectional view of the modification of the game taken on the plane of the line 5—5 of Fig. 4.

Referring to the accompanying drawings in which like numerals indicate like parts throughout the several views, the numeral 10 indicates

generally the rotatable body of the game which is mounted for rotation about a pin 11 arranged with its axis inclined. The pin 11 is carried by a support 12 of any suitable construction and shown in the present instance as comprising two supporting legs 13 and 14 hingedly connected as at 15. The pin 11 is fixed to the leg 14, which, to insure rigidity, is wide at its base.

The legs of the support may be connected to prevent their spreading apart, or the support may be set up in the body 16 of an enclosing box within which the entire game is housed when not in use, with the leg 13 abutting one outer wall of the body and the leg 14 engaging a stop 17 fixed to the bottom of the box.

The portion 18 of the box body forwardly of the stop 17 provides a convenient receptacle for the scoring members to be later described during the playing of the game.

The rotatable body 10 of the game is susceptible to various constructions and in the present instance, consists of a disc 19 of wood or other suitable material upon one face of which a transverse strip 20 is secured. This transverse strip 20 extends diametrically across the disc 19 and has its opposite end portions cut away to provide spaced walls 21 which together with the disc 19 and a cover 22 mounted on top of the transverse strip, define a pair of tunnels or passageways 23 extending from the outer periphery of the unit 30 inwardly to a point closely adjacent its center.

The central portion 24 of the transverse strip is left solid and together with the disc 19 is bored to receive the pin 11. To reduce friction and wear, metal washers 25 and 26 may be fastened to the undersurface of the disc 19 and the outer face of the transverse strip 20. Obviously, the washer 25 rests on the outer face of the supporting leg 14 and thus spaces the disc 19 of the rotatable body therefrom.

Encircling the disc 19 and the cover disc 22 is an upstanding circular side wall 27. This wall is preferably formed of sheet metal and is secured to the discs 19 and 22 in any suitable manner, and inasmuch as it extends above the cover disc 22, serves to close the ends of the tunnels or passageways 23.

Inasmuch as the circular side wall 27 extends above the cover disc 22, it cooperates therewith to form a flat cylindrical chamber or space. This flat cylindrical space is divided into a plurality of concentric channels 28 by a plurality of concentric annular partitions 29. The partitions 29 in the present instance are shown as substantially channel shaped in cross section with their inner

55

flanges 30 riveted or otherwise secured to the cover disc 22 and their outer flanges 31 overlying the annular channels 28 to partially close the same for a purpose to be later described.

5 The number of partitions 29 is so chosen as to leave a central chamber 32 of sufficient diameter to extend over the inner ends of the tunnels or passageways 23 a distance substantially equal to the width of the annular channels 28, the cover disc 22 having openings 33 therethrough to communicate the inner end of each tunnel or passageway with the central chamber 32.

10 The scoring member or members 34, which may be spheres or any other suitably shaped elements 15 of a size to permit them to travel in the tunnels or passageways and in the annular channels, are thus free to pass from the inner chamber 32 into either of the tunnels or passageways 23 and vice versa. To facilitate the scoring members rolling 20 from a tunnel or passageway when the same is uppermost down into the central chamber, the inner ends of the tunnels or passageways are curved toward the central chamber.

15 Communication is also afforded between the 25 tunnels or passageways and each of the annular channels 28, but this communication is adapted to be controlled in a manner now about to be described.

20 The openings 33 which communicate the tunnels or passageways with the central chamber, 30 are extended as radial slots 33' and from the innermost annular partition 29 which defines the central chamber 32, these radial slots have downwardly offset longitudinal guideways 35. Mounted 35 in the guideways 35 are slide plates 36, the outer surface of which is flush with the cover disc 22. These slide plates 36 are of a length to extend from the outside of the side wall 27 to a point adjacent the innermost annular partition 40 and, as clearly illustrated in Figure 2, close off communication between the annular channels and the tunnels or passageways except as determined by openings 37 in the plates. The 45 openings 37 are positioned to align with the annular channels and their number and location determines the annular channels to be communicated with the tunnels or passageways and depends upon the particular game to be played.

50 Finger engaging portions or handles 38 are provided at the outer ends of the slide plates to facilitate their insertion and removal.

55 Obviously, the greater the number of channels communicated with the passageways, or tunnels, the faster will be the travel of the scoring members 34 from one channel into the other by means of the tunnels or passageways.

60 Besides the communication afforded between the several annular channels by the tunnels or passageways, the walls or partitions 29 have openings 39 at staggered intervals to permit the scoring members to pass therethrough from one channel into the other as the unit rotates.

65 The outer circular wall 27, which provides the outer wall for the outermost annular channel 28, has a single opening 40 of a size just sufficient to permit the scoring members 34 to pass singly therethrough. Through this opening, the scoring members may be discharged from the unit when the unit is in a position of rotation at which 70 the opening 40 is at the bottom; and when a scoring member leaves the unit in this manner, it may be eliminated from play or may determine a score, depending upon the particular game being played.

75 To insure the scoring members which leave

the unit through the opening 40 being discharged at a single desired point, a guide 41 is carried by the leg 14 of the supporting stand.

80 This guide 41 has a circular wall 42 overlying the lower portion of the rotatable unit with an opening 43 at its extreme lower portion so that the discharge of a scoring member through the opening 40 is guided and the member drops into the chamber 18.

85 The manner of scoring may be greatly varied 10 and many varieties of individual and distinct games may be played with the same structure. An extremely simple method of scoring is one in which the players choose scoring members of different colors and the one whose scoring member is last eliminated through the opening 40 wins the game. However, a more interesting game is afforded by providing indicator elements 44 which have different scoring indicia 45 arranged thereon in concentric circles to overlie 15 the outer flanges 31 of the partitions 29.

90 In the embodiment of the invention illustrated in Figures 1 and 2, the indicator elements are in the shape of wide flat rings of glass, celluloid, or any other suitable transparent material and are readily detachably held in position over the open tops of the annular channels by tangs 46 which are adapted to be bent down over the outer face of the indicator element as illustrated. The scoring indicia, as stated, is arranged in 95 rings to overlie the flanges 31 on the partition walls and is divided by means of colors into spaced segments each having a particular value depending upon the game for which the indicator is designed so that when the rotatable unit and the scoring members come to rest, their particular position with reference to the scoring indicia determines a score.

100 Inasmuch as the scoring indicia is opaque, the indicator units may be applied one above the other as illustrated in Figures 1 and 2.

105 In the embodiment shown, the indicator elements do not extend across the innermost annular channel or across the central chamber 32 which is shown covered by a glass disc 47 having a central opening 48 to permit the insertion of scoring members, but as will be readily apparent, the indicator elements may be discs arranged to extend across all of the channels and also across the central chamber.

110 As hereinbefore stated, the outer flanges 31 of the partition walls 29 overlie the annular channels so that the indicator members 34 are thereby prevented from outward displacement, and if desired, the flanges 31 may have scoring indicia printed directly thereon or applied thereto by removable indicator rings 49 as illustrated in Figure 4, the indicator rings 49 being readily removably held in position by tangs 50.

115 Also, the outer walls of the annular channels may be scalloped as at 51, (see Figure 4) to insure the scoring members coming to rest at definite positions with respect to the scoring indicia.

120 While Figure 4 shows the outer walls of the channels scalloped to insure the scoring members coming to rest at definite positions with respect to the scoring indicia, the same result may be obtained by depressing the outer walls of the annular channels or providing apertures therein of a diameter less than the diameter of the scoring members.

125 During playing of any of the games for which the structure is suited, the scoring members are first inserted into the central chamber 32

- through the opening 48 and the rotatable body affording an auxiliary communication between given an impulse which sends the individual channels scoring members back and forth from one channel into the other and through the tunnels or members rotatable about an inclined axis, said 5 passageways back into the central chamber until the unit comes to rest with the scoring members channels communicating with each other, aligned with different sections of the scoring spaced points, a scoring member free to travel in indicia or eliminated from the unit through the channels and from one channel to another discharge opening 40 upon rotation of the rotatably mounted member, 5. In a game of the character described, a member having a plurality of concentric annular channels communicating with each other, aligned with different sections of the scoring spaced points, a scoring member free to travel in indicia or eliminated from the unit through the channels and from one channel to another discharge opening 40 upon rotation of the rotatably mounted member, 5
- 10 From the foregoing description taken in connection with the accompanying drawings, it will be readily apparent to one skilled in the art, that this invention affords a game which is extremely fascinating by reason of the uncertainty of the result and the fact that the scoring members are visible in their travel back and forth from one channel to the other during the operation of the game, and while the structure has been illustrated and described as built up of separate pieces, it will be readily apparent that the entire rotatable unit may be easily molded of fibre, a phenol condensation product, or any other suitable moldable substance.
- What I claim as my invention is:
- 25 1. In a game of the character described, a member rotatable about an inclined axis, said member having a plurality of concentric annular channels communicating with each other at spaced points, a scoring member free to travel in the channels and from one channel to another upon rotation of the rotatably mounted member, retaining means to prevent the outward displacement of the scoring member from said channels, and means for communicating certain of the annular channels independently of their aforesaid communication.
2. In a game of the character described, a member rotatable about an inclined axis, said member having a plurality of concentric annular channels communicating with each other through radial openings at staggered intervals, a scoring member free to travel from the inner channel through the staggered radial openings to the outer channel upon rotation of the rotatably mounted member, a passageway for the return of the scoring member from an outer channel independently of the aforesaid staggered radial openings, and suitable scoring indicia adjacent each channel for cooperating with the scoring member upon its coming to rest in an annular channel to indicate a score.
3. In a game of the character described, a rotatably mounted member, said member having a plurality of concentric annular channels communicating with each other through radial openings at staggered intervals, a scoring member free to travel from the inner channel through the staggered radial openings to the outer channel upon rotation of the rotatably mounted member, a passageway permitting travel of the scoring member from one channel to another channel independently of the aforesaid staggered radial openings.
4. In a game of the character described, a member rotatable about an inclined axis, said member having a plurality of concentric annular channels communicating with each other at spaced points, a scoring member free to travel in the channels and from one channel to another upon rotation of the rotatably mounted member, a passageway connecting all of the annular channels, and means for closing the passageway at certain of the channels whereby other channels are connected with the passageway and thereby a passageway for the return of the scoring member from an outer channel to an inner channel, aligned with different sections of the scoring spaced points, a scoring member free to travel in indicia or eliminated from the unit through the channels and from one channel to another discharge opening 40 upon rotation of the rotatably mounted member, 10
- 15 6. In a game of the character described, a rotatably mounted member, said member having a plurality of concentric annular channels communicating with each other through radial openings at staggered intervals, a scoring member free to travel from the inner channel through the staggered openings to the outer channel upon rotation of the rotatably mounted member, a passageway permitting travel of the scoring member from one channel to another channel independently of the aforesaid staggered openings, and suitable scoring indicia adjacent each channel for cooperating with the scoring member upon its coming to rest in an annular channel to indicate a score.
7. In a game of the character described, a member rotatable about an inclined axis, said member having a plurality of concentric annular channels on its upper surface communicating with each other at staggered intervals, a scoring member free to travel in the channels and from one channel to another upon rotation of the rotatably mounted member, means to return the scoring member from an outer channel to an inner channel, and removable means overlying part of each channel carrying suitable scoring indicia cooperating with the scoring member upon its coming to rest in an annular channel to indicate a score.
8. In a game of the character described, a member rotatable about an inclined axis, said member having a plurality of concentric annular channels communicating with each other at staggered intervals, a scoring member free to travel in the channels and from one channel to another upon rotation of the rotatably mounted member, means to return the scoring member from an outer channel to an inner channel, a plurality of removable means overlying part of each channel and superimposed one on the other and carrying suitable indicia for cooperating with the scoring member upon its coming to rest in an annular channel to indicate a score, said means being readily removable to expose the indicia of a lower removable means.
9. In a game of the character described, a member rotatable about an inclined axis, said member having a plurality of concentric annular channels communicating with each other at staggered intervals, a scoring member free to travel in the channels and from one channel to another upon rotation of the rotatably mounted member, means to return the scoring member from an outer channel to an inner channel, a plurality of removable means overlying part of each channel and superimposed one on the other and carrying suitable indicia for cooperating with the scoring member upon its coming to rest in an annular channel to indicate a score, said means being readily removable to expose the indicia of a lower removable means.
10. In a game of the character described, a member rotatable about an inclined axis, said member having a plurality of concentric annular channels communicating with each other at staggered intervals, a scoring member free to travel in the channels and from one channel to another 15 20 25 30 35 40 45 50 55 60 65 70 75

upon rotation of the rotatably mounted member, means to return the scoring member from an outer channel to an inner channel, a plurality of indicator elements each bearing distinct and 5 different indicia with each indicator element representing an individual game, and means to readily detachably mount any one of said plurality of indicator elements on the rotatable member to cooperate with the scoring member 10 upon its coming to rest in an annular channel to indicate a score.

11. In a game of the character described, a member rotatable about an inclined axis, said member having a plurality of concentric annular 15 channels communicating with each other at spaced points, a scoring member free to travel in the channels and from one channel to another upon rotation of the rotatably mounted member, means to return the scoring member from an 20 outer channel to an inner channel, and a transparent element covering all of the concentric annular channels and having suitable indicia arranged in circles between the channels to cooperate with the scoring member upon its coming 25 to rest in an annular channel to indicate a score, and means for holding the transparent element in position.

12. In a game of the character described, a member rotatable about an inclined axis, said 30 member having a plurality of concentric annular channels communicating with each other at spaced points, a scoring member free to travel in the channels and from one channel to another upon rotation of the rotatably mounted member, 35 means to return the scoring member from an outer channel to an inner channel, and a transparent element covering the concentric annular channels and having suitable indicia arranged in circles between the channels to cooperate with 40 the scoring member upon its coming to rest in an annular channel to indicate a score, and tangs carried by the rotatable member adapted to be bent over the transparent element to secure the same in position.

45 13. In a game of the character described, a member rotatable about an inclined axis, said member having a plurality of concentric annular channels communicated with each other at spaced points, a scoring member free to travel in

the channels and from one channel to another upon rotation of the rotatably mounted member, suitable scoring indicia adjacent each channel, means preventing the outward displacement of the scoring member from said channels, a passageway connecting with all of the annular channels, and removable means for closing the passageway at certain of the channels whereby the other channels are connected with the passageway, thereby affording an auxiliary connection 10 between said other channels, and the outermost wall of said channels being scalloped to hold the scoring member upon its coming to rest in a predetermined position in respect to the scoring 15 indicia.

14. In a game of the character described, a stationary support, a rotatable member mounted on said support, said rotatable member having concentric tracks adapted to have a scoring member roll therein, said tracks being communicated whereby the scoring member is free to pass from one track to the other, means at the center of said rotatable member to hold the scoring member and feed the same to one of the concentric tracks, means to return the scoring member from the outermost track to said last named means, and scoring indicia on said rotatable member adjacent the concentric tracks with which the scoring member cooperates upon coming to rest to indicate a score.

15. In a game of the character described, a rotatable member, a fixed support to mount said rotatable member for rotation about an inclined axis, said rotatable member having a plurality of communicated concentric tracks adapted to have 35 a scoring marble run therein and pass from an inner track to an outer track, means at the center of said rotatable member to receive and conduct the scoring marble to one of the tracks, means to return the scoring marble from the outermost track to said last named means, means in said tracks defining positive stops for the marble to hold the same in definite locations, and scoring indicia around said tracks so located with respect to said stops as to cooperate with the 40 marble upon the same coming to rest to indicate a score.

FRANK C. WACHS.
